UNITED STATES PATENT OFFICE

JOHN C. F. SCHAFER, OF MOUNT PULASKI, AND JOSEPH F. BLESER, OF SPRINGFIELD, ILLINOIS; SAID BLESER ASSIGNOR TO SAID SCHAFER

DAMPER

Application filed January 4, 1932. Serial No. 584,638.

Our invention relates to improvements in dampers, and more particularly to a damper having means thereon to conveniently and accurately perforate a stove pipe in which 5 the damper is to be inserted, for the mounting of the damper therein in proper position.

The invention has among its objects, the production of a damper of the kind described, having a detachable damper rod which may 10 be used for perforating a stove pipe upon diametrically opposed sides of the wall of the same at a predetermined distance from the end of said pipe, while holding the pipe steady without wobbling, or without wobbling of the perforating means.

Other objects of the invention include the production of a damper of the kind described, in which the damper plate will straddle the end of the pipe when it is desired to perforate the latter to receive the damper rod, said plate having a threaded portion upon one of the straddling legs so that the damper rod may be fed therethrough, and the other leg is bent to either side of the plane of the plate 25 and terminates above the threaded portion of the first leg, so as to form a good support to engage against the inner surface of the pipe while perforating the pipe.

Still further objects of the invention are 30 the construction of the same wherein the same will be neat in appearance, simple and sturdy in construction, compact, easy to operate either for the perforating of the pipe or when in normal use, reliable, and efficient and satisfactory for use wherever found applicable.

Other objects and advantages of the construction herein shown and described will be 40 obvious to those skilled in the art to which this invention appertains, from the disclosures herein given.

In the drawing, wherein like reference characters indicate like or corresponding 45 parts throughout the views,

Figure 1 is a plan view of the damper in normal use within a stove pipe;

Figure 2 is a side elevation of the same, with the damper rod about to perforate the 50 pipe;

Figure 3 is a perspective view of the damper plate, with the rod removed; and

Figure 4 is a cross-sectional view, taken substantially along the line 4-4 of Fig. 3.

Referring more particularly to the drawing, wherein we have illustrated the preferred embodiment of our invention, A indicates one end of a length of stove pipe, and generally made of sheet iron or the like, and in which it is desired to place a damper for 60 the usual purpose of controlling the passage of the smoke or gases therethrough.

The damper is indicated generally as B, and comprises a plate 1 of a shape to fit easily within the pipe A to substantially close the 65 passage therethrough, and in the form shown is somewhat circular in outline. The plate may be made in any desired manner, as by stamping, casting or the like, and may be fairly thin, as shown.

A transverse or diametrically extending slit 2 is provided in the plate, from the periphery of the same to adjacent the opposite peripheral point, to thereby form a pair of legs 3 and 4 adapted to straddle one end of the pipe 75 A, when it is desired to perforate the pipe for the damper rod bearings, as will soon be set forth more clearly.

Across the damper plate in a diametral line normal to the direction of the slit 2 are damper rod supporting means, consisting of concavo-convex pairs of members 5 and 6 at either side of the slit, the members of each pair being curved oppositely to one another to form a circular bearing for the damper 85 rod that is positioned therethrough when the latter is in its normal position, and in addition, the members of one pair have the notches 7 to accommodate the projections 8 carried by the damper rod, and to limit the longitudinal movement of the latter within its 90 bearings on the plate.

The damper rod R may be provided with means for grasping the same for proper manipulation thereof when it is desired to operate the damper, and this may be done by offsetting the projecting end of the latter at an angle so as to provide the handle portion 95 9. A coiled spring 10 may be interposed between this handle portion and the stove pipe, 100

so as to normally keep the parts in the position shown in Fig. 1.

- Pushing inwardly on the damper rod will cause the projections 8 to disengage from the notches 7, so that the rod may then be partially rotated and then withdrawn longitudinally outwardly from its bearings in the plate until the innermost projection 8 is adjacent the outermost notch 7, and whereupon further partial rotation of the rod will throw the notch and projection out of alignment again and permit further longitudinal movement of the rod and complete withdrawal of the latter from the plate.
- The end of one of the legs, as for example the leg 4, is provided with a concavo-convex damper-rod receiving member 11, suitably provided with screw threads 12 therealong so as to threadedly receive the correspondingly threaded portion 13 of the damper rod and permit of the feeding of the rod therethrough as the rod is rotated therein. The damper rod is also sharpened or provided with a pointed end 14, to perforate the pipe when fed through the member 11.

In order to provide a firm support behind the wall of the pipe being perforated, the other leg 3 of the plate is formed with an abutment at said slit 2, this abutment preferably being formed by bending the material of the plate outwardly from the plane of the plate as at 15, and thence more sharply bent to extend in the opposite direction beyond the plane of the plate, as at 16. Thus the abutment is so formed as to extend to both sides of the median plane of the plate at the slit and thus provide a good and full bearing to engage against the inner surface of the wall of the stove pipe, to permit of rapid and easy perforating of the pipe from the exterior of said wall, as the rod R is fed through the threaded guide means 11. It is also to be noted that the abutment thus provided terminates above the axis through the member 11, and hence there is no likelihood of this abutment ever interfering with free passage of the rod through the pipe when perforating the latter.

When it is desired to perforate the stove pipe in order to mount the damper within the pipe, the plate is placed so as to have the legs 3 and 4 straddling the end of the pipe, and then the damper rod (which has been previously disengaged from its normal position on the plate) is then screwed through the member 11, continued rotation of the rod feeding the same longitudinally to press the point into the pipe and drawing the abutment 15-16 firmly against the inner surface of the pipe substantially thereat, and thence properly perforate the pipe. The plate is then moved to a diametrically opposite position to again straddle the pipe, and a second perforation made in the same manner, through the stove pipe, the perforations thus made being

necessarily made at the same distance below the top of the pipe and in the same plane, to assure perfect positioning of the damper rod within these aligned apertures to serve its normal function as an axle for the damper plate.

Since the free end of the abutment terminates above the axis of the member 11, an open space is thus always provided between said abutment and the opposed surface of the stove pipe to permit of some draft through the pipe even when the damper is fully closed, and hence there will be no excessive smoking caused by a full closure of the damper plate, this constantly open and unobstructed space being in addition to the space provided by the slit 2.

Having thus described our invention, it is obvious that various immaterial changes and modifications may be made in the same without departing from the spirit of our invention; hence we do not wish to be understood as limiting ourselves to the exact form, arrangement, construction and combination herein shown and described, except as limited by the state of the art to which this invention appertains, or the claims hereto appended.

What we claim as new and desire to secure by Letters Patent is:

1. A damper for a pipe, comprising a plate of substantially uniform thickness throughout and having a slit extending inwardly from the periphery to enable the plate to straddle said pipe; a pointed screw-threaded damper rod removably mounted on said plate; screw-threaded means on said plate at one side of said slit to receive and guide the threaded rod during the perforating of the pipe; and an abutment formed from said plate on the opposite side of said slit and extending to both sides of said plate to engage the interior wall of the pipe when the latter is straddled by said plate and said rod is rotatably fed in said threaded guiding means.
2. A damper for use within a pipe and comprising a plate having a diametral slit open at one end to form a pair of legs to straddle an end of said pipe; a threaded damper rod removably mounted on said plate and provided with a pointed pipe-perforating end; a threaded damper rod support on one of said legs adjacent said slit and whose axis is in the median plane of the plate; and an abutment formed on the other leg of said plate by bending the latter alternately to either side of the median plane of the plate and which will abut the interior of said pipe when the plate straddles the latter and the rod is rotated within said threaded support.
3. A damper for a pipe, comprising a disk having a pair of legs spaced apart by a slit, so as to straddle one end of said pipe when perforating the latter; a damper rod detachably mounted on said plate and threaded and provided with a pointed end; a threaded rod

guide on one of said legs to receive said rod only when it is desired to perforate said pipe with the latter; and an abutment of uniform cross-sectional thickness with said plate 5 and formed on the other leg of said plate by bending the same alternately to either side of the plate and terminating inwardly of the ends of said legs above said threaded guide, so that when the plate straddles the 10 pipe and the rod is rotated within said threaded guide, said abutment will engage the interior wall of the pipe beyond said rod while the pipe is pierced with said pointed end of the rod.

15 4. A damper for use within a pipe and comprising a plate having a diametral slit whereby the plate may straddle an end of said pipe, and with damper rod supporting means diametrically thereacross normal to 20 said slit; a screw-threaded damper rod removably insertable in said means and provided with a pipe-perforating end; screw-threaded guide means on said plate adjacent the open end of said slit to receive said 25 threaded rod when piercing the pipe; and an abutment forming a permanent integral part of said damper and extending to either side of said plate at said slit to engage said interior of said pipe when the plate straddles 30 the pipe and the rod is rotated within said guide to feed against and perforate said pipe.

In testimony whereof, we have affixed
our signatures.

JOHN C. F. SCHAFER.
JOSEPH F. BLESER.
